UNITED STATES PATENT OFFICE

WILLIAM C. MILLER, OF CANTON, OHIO, ASSIGNOR TO DIEBOLD SAFE & LOCK COMPANY,
A CORPORATION OF OHIO

SAFE

Application filed June 6, 1932. Serial No. 615,701.

The invention relates to safes and particularly to safes or money-chests in which the daily receipts of stores, etc., may be placed temporarily for safe keeping.

5 A safe or money-chest of this type is shown in my co-pending application Serial No. 511,893, filed January 28, 1931.

The primary object of the invention is to provide an improved money-chest of the 10 character described in which money may be deposited without opening it.

One form of the present invention is embodied in a heavy-walled container embedded in a lock of concrete, the container being 15 provided with a round door-opening which is normally closed by a closure-member adapted to be lifted bodily from the container when the contents thereof are to be removed therefrom. The wall of the container is provided with a money-slot which extends from the cylindrical surface of the door-opening to the interior of the container. Means is provided for locking the closure-member to the container in such manner that 20 the closure-member may be displaced longitudinally of the door-opening to cover and uncover the money-slot so that money may be deposited in the container even though the closure-member remains secured to the 25 container and cannot be lifted bodily therefrom. The locking means may be manipulated to lock the closure member against any movement whatever when it is in the position wherein it covers the money-slot.

30 Other advantages and objects will become apparent as the following detailed description progresses, reference being had to the accompanying drawings, wherein—

Fig. 1 is a vertical central section taken 40 through a money-chest which embodies the invention.

Fig. 2 is a fragmentary plan view of the improved device.

Fig. 3 is a section taken on line 3—3 of 45 Fig. 2.

Fig. 4 is a fragmentary plan view of the improved device with its door or closure member removed.

Fig. 5 is a bottom plan view of the door or 50 closure member for the improved device.

Fig. 6 is a section taken on line 6—6 of Fig. 2.

Fig. 7 is a section taken on line 7—7 of Fig. 6.

Fig. 8 is a section taken on the same line 55 as Fig. 6, but the door or closure member is shown in a different position, and

Fig. 9 is a section taken on line 9—9 of Fig. 6.

Referring to the drawings wherein a preferred embodiment of the invention is illustrated, the reference character A designates a block of concrete which is housed in a sheet metal shell B; C, a money-chest embedded in the concrete block A, and D, a closure member for the money-chest C.

The concrete block A is preferably of such dimensions that it may be placed in a store, theatre, etc., in a convenient position so that 70 money may be deposited therein from time to time, the concrete block being preferably of such weight that it cannot be removed readily from the premises.

The sheet metal shell B may be of any suitable construction. In this instance, it comprises a bottom wall 10, four vertical side walls 11 and a top wall 12. The side walls 11 are reenforced by angle irons 13 which have legs projecting into the concrete block A. The block A is preferably formed in the 80 shell B.

The money-chest C preferably comprises a one-piece container 20 which is preferably formed from cast steel. It will be noted that the walls of the container 20 are relatively 85 thick and that the container is provided with annular flanges 21 and 22 at its top and bottom, respectively. The flange 21 fits snugly in a hole 24 formed in the top wall 12 of the shell B. The flange 22 projects into the concrete block A and anchors the container 20 therein. It will be noted, however, that the container 20 is of such shape that it anchors 90 itself in the concrete block A. Thus, the container is provided with a neck portion 25 of reduced diameter so that the body portion of the container cannot be removed from the concrete block unless a relatively large portion of the concrete block is broken away. The neck portion 25 is provided with a door 100

opening 27 for the door D which, when it is in its closed position, closes the outer end of a money slot 28, the inner end of the money slot 28 being formed so that money, etc. may drop from it into the container 20 (see Fig. 1). The money slot 28 is preferably curved to prevent unauthorized persons from fishing through it with instruments to withdraw money from the container.

10 As best shown in Figures 4, 6 and 8, the container 20 is provided with integral lugs 30, 31 and 32 which project into the door opening 27, the lugs 30, 31 and 32 being disposed in the inner end of the door opening. It will be noted that the lugs 30, 31 and 32 are spaced from each other to provide a bayonet-slot construction which co-operates with the lugs, hereinafter described, provided upon the door D. In this instance, the lug 30 is shorter than the lugs 31 and 32.

15 As shown in Fig. 7, the container 20 is provided with a hardened steel plug 35 having a bore or recess 36 which is engageable by a locking bolt 37 associated with the door D. 20 When the bolt 37 is in the position wherein it is shown in Fig. 7, the door D is locked to the container 20 in such manner that it cannot be removed therefrom and cannot be angularly displaced around the vertical longitudinal axis of the container.

25 The plug 35 is disposed in a bore 39 formed in the neck portion 25 of the container 20, the bore 39 being provided with an annular shoulder 40 which co-operates with a head portion 41 on the plug 35 to prevent unauthorized persons from driving the plug into the container. The outer end of the bore 39 is filled with a steel plug 43 which is welded to the container as indicated at 44.

30 The plug 35 is notched as at 45 so that when the bolt 37 is partially retracted from the position wherein it is shown in Fig. 7, it may pass through the notch 45 into a slot 46 formed in the inner surface of the neck portion 25. The slot 46 comprises an arcuate portion 46a and a downwardly extending portion 46b. The purpose of this construction will presently appear.

35 The door D preferably comprises a body portion 50 formed from cast steel, the body portion 50 being provided with an annular downwardly extending flange 51 which forms a chamber 52 for a lock 53. The bottom wall of the chamber 52 being formed by a plate 55 which is secured to the body portion 50 by screws 56. Formed integral with the body portion 50 and projecting radially from the flange 51 are two rows of lugs, one row being disposed above the other (see Figs. 5, 6, 7, 8 and 9). The bottom row of lugs comprises three lugs 60, 61 and 62. The upper row comprises three lugs 64, 65 and 66. The lug 61 is longer than the lugs 60 and 62 and is adapted to pass between the lugs 30 and 31 on the container. The lug 61 is too long, how-

ever, to pass between the lugs 30 and 32 or the lugs 31 and 32. This construction insures that the closure member 50 will be lowered into the door opening 27 in such manner that the bolt 37 may engage the bore 36 if the closure member is angularly displaced a relatively small angular distance after the closure member has been lowered to the position wherein it is shown in Fig. 6. Fig. 7 illustrates the manner in which the closure member D is locked to the container 20 after the closure member has been lowered to the position illustrated in Fig. 6 and then rotated in the door opening to bring the bolt 37 into registry with the bore 36. When the closure member D has been angularly displaced to bring the bolt 37 into registry with the bore 36, the lugs 60, 61 and 62 will lie beneath the lugs 30, 31 and 32, respectively, to lock the closure member to the container. In other words, one cannot remove the closure member D from the container 20 by pulling on the closure member with sufficient force to break or bend the bolt 37.

40 The lock 53 is of the type which must be manipulated with two keys if the bolt 37 is to be brought into its fully retracted position so that the closure member may be lifted out of the door opening 27. As shown in Fig. 2, the lock 53 is provided with two lock noses 70 and 71 provided with the usual keyholes through which keys may be inserted to operate the lock mechanism. In this instance, the lock noses 70 and 71 extend into recesses 74 formed in the body portion 50 of the closure member and bores 75 extend from the top surface of the closure member to the recesses 74 so that the keys may be passed through the bores 75 to the lock noses.

45 The lock 53 is provided with a bolt 77 to which an arm 78 of a bell crank lever 79 is pivoted. The bell crank lever 79 being provided with an arm 80 which is pivoted by a pin 81 to one end of a link 82 (see Figs. 3 and 7). The bell crank lever 79 is pivoted by a pin 83 to the body portion 50. The other end of the link 82 is pivoted to the bolt 37 by a pin 86. The pin 86 projects into a hole 87 drilled in a plug 89 which is slidably journaled in a bore 90 formed in the bolt 37. A compression spring 92 is disposed between the plug 89 and the inner end of the bore 90. Projecting downwardly from the body portion 50 and aligned with the plug 89 is a stop pin 94 (see Figs. 3 and 7).

50 If an attempt is made to gain access to the interior of the container 20 by hammering on the lock noses 70 and 71 to drive the lock 53 from its position on the bottom surface of the body portion 50, such displacement, if successful, will drive the link 82 downwardly so that it will withdraw the pin 86 from the hole 87 or from both the hole 87 and the bolt 37. The spring 92 will then expand and drive the plug 89 back against the stop pin 130

94, the bolt 37 being retained in its fully extended position. This construction insures that the closure member D will remain locked to the container 20.

5 One of the two keys employed to manipulate the lock 53 is kept on the same premises as the improved money-chest, the other key being preferably in the possession of some agency which makes daily collections of 10 money, etc. deposited in the container 20. The lock 53 is of such construction that when it is manipulated solely by the key kept on the premises, the bolt 37 may be retracted a short distance so that the closure member D 15 may be angularly displaced in the door opening 27. When the closure member is angularly displaced in this manner, the outer end of the bolt 37 passes through the notch 45 and the arcuate portion 46a of the slot 46 to a position 20 wherein it registers with the portion 46b of the slot 46. The lugs 64, 65 and 66 are then disposed directly over the spaces between the lugs 30, 31 and 32 and the closure member may be lowered until the body portion 25 50 rests upon the upper surfaces of the lugs 30, 31 and 32. It will be noted that the body portion 50 is provided with a shoulder 50a for this purpose (see Fig. 8). This downward displacement of the closure member uncovers the outer end of the slot 28 and permits money to be dropped into the container. After the money has been deposited in the container, the closure member may be 30 lifted to the position wherein it is shown 35 in Fig. 6 and rotated to bring the bolt 37 into registry with the bore 36 whereupon the key on the premises may be employed to return the bolt to its fully extended position.

When the money, etc. in the container is to 40 be removed therefrom, both keys are employed to manipulate the lock 53 so that the bolt 37 is withdrawn entirely from the bore 36. The closure-member D is then angularly 45 displaced a short distance in a counter clockwise direction (Fig. 7) to bring the lug 61 into registry with the space between the lugs 30 and 31, whereupon the closure member D may be lifted bodily from the container.

While I have shown and described certain 50 embodiments of my invention, it is to be understood that it is capable of many modifications. Changes, therefore in the construction and arrangement may be made without departing from the spirit and scope of the invention as disclosed in the appended claims, in which it is my intention to claim all 55 novelty inherent in my invention as broadly as possible, in view of the prior art.

I claim:

60 1. A deposit-safe comprising: a container having a door-opening therein and having a slot in its wall extending from said door-opening to the interior of the container; a closure-member for said door-opening; and means for locking said closure-member to said

container, said closure-member being movable longitudinally of said door-opening, while it is locked to said container, to cover and uncover the outer end of said slot.

2. A deposit-safe comprising: a container 70 having a door-opening therein and having a slot in its wall extending from said door-opening to the interior of the container; a closure member for said door-opening; and means for locking said closure-member to said container, said closure-member being adapted to be angularly and longitudinally displaced in said door-opening, while it is locked to said container, to cover and uncover the outer end of said slot.

3. A deposit-safe comprising: a container having a door-opening and having a money-slot in its wall extending from said door-opening to the interior of the container, said container being provided with a plate-receiving recess, an arcuate slot and a longitudinally extending slot in said door-opening; a closure-member for said door-opening; a locking bolt carried by said closure-member; and a lock for displacing said bolt into a fully extended position, a partially retracted position, and a fully retracted position, said bolt being engageable in its fully extended position with said recess to lock said closure member against any displacement relative to said container and being adapted to ride in said arcuate slot and said longitudinally extending slot when it is in its partially retracted position, said closure-member being adapted to be angularly and longitudinally displaced in said door-opening, when said bolt is in its partially retracted position, to cover and uncover the outer end of said money-slot.

4. A deposit-safe comprising: a container having a door-opening and a money-slot extending through its wall from said door-opening to the interior of the container, said container being provided with a bolt-receiving recess, an arcuate slot and a slot extending longitudinally of said door-opening; a closure-member for said door-opening; and means including a bolt carried by said closure-member for locking said closure-member to said container, said bolt being engageable with said recess to lock the closure-member against any movement relative to the container and said bolt being engageable with said arcuate slot and said longitudinally extending slot to permit the closure-member to be angularly and longitudinally displaced in said door-opening, while it remains locked to said container, to cover and uncover the outer end of said money-slot.

5. A deposit-safe comprising a heavy-walled container having a round door-opening therein and having a money-slot extending through its wall from said door-opening to the interior of the container, said container being provided with inwardly extending spaced lugs in said door-opening; a clo-

sure-member for said door-opening having two sets of outwardly extending lugs engageable with the lugs on said container, one set of lugs on said closure-member being spaced 015 from the other set longitudinally and angularly of said closure-member, one of said sets of lugs being engageable with the lugs on the container to prevent withdrawal of said closure-member therefrom until said closure- 020 member has been rotated into a predetermined position in said door-opening and the other of said sets of lugs being adapted to pass through the lugs on the container so that the closure-member may be displaced longitudi- 025 nally in said door-opening to cover and uncover the outer end of said money-slot; and means for locking said closure-member to said container.

6. A deposit-safe comprising: a heavy- 030 walled container having a round door-opening therein and having a money-slot extending through its wall from said door-opening to the interior of the container, said container being provided with inwardly extending spaced lugs in said door-opening; a closure-member for said door-opening having two sets of outwardly extending lugs engageable with the lugs on said container, one set of lugs on said closure-member being spaced 035 from the other set longitudinally and angularly of said closure-member, one of said sets of lugs being engageable with the lugs on the container to prevent withdrawal of said closure-member therefrom until said closure- 040 member has been rotated into a predetermined position in said door-opening and the other of said sets of lugs being adapted to pass through the lugs on the container so that the closure-member may be displaced longitudi- 045 nally in said door-opening to cover and uncover the outer end of said money-slot; and means for locking said closure member against any displacement in said door-opening, said locking means being adjustable to permit angular and longitudinal displacement of said closure-member in said door-opening while it remains secured to said container.

7. A deposit-safe comprising: a heavy- 050 walled container having a round door-opening therein and having a money-slot extending through its wall from said door-opening to the interior of the container, said container being provided with inwardly extending spaced lugs in said door-opening and said container being provided with a bolt-receiving recess, an arcuate slot and a longitudinally extending slot in said door-opening; a closure-member for said door-opening having two sets of outwardly extending lugs engageable with the lugs on said container, one set of lugs on said closure-member being spaced 055 from the other set longitudinally and angularly of said closure-member, one of said sets of lugs being engageable with the lugs on the

container to prevent withdrawal of said closure-member therefrom until said closure-member has been rotated into a predetermined position in said door-opening and the other of said sets of lugs being adapted to 70 pass through the lugs on the container so that the closure-member may be displaced longitudinally in said door-opening to cover and uncover the outer end of said money-slot; and means for locking said closure-member to 75 said container including a bolt engageable with said bolt-receiving recess and said arcuate and longitudinally extending slots in said door-opening.

8. A deposit-safe comprising: a heavy- 80 walled container having a door-opening and having a money-slot extending from said door-opening to the interior of the container; and a closure-member for said door-opening, said closure-member slidable back and forth 85 in said door-opening to cover and uncover the outer end of said money-slot.

9. A deposit-safe comprising: a heavy- 90 walled container having a door-opening and having a money-slot extending from said door-opening to the interior of the container; a closure-member for said door-opening, said closure-member slidable back and forth in 95 said door-opening to cover and uncover the outer end of said money-slot; and means for holding said closure-member locked to said container while it is being moved back and forth in said door-opening.

In witness whereof, I have hereunto subscribed my name this 13th day of May, 1932.

WILLIAM C. MILLER.
